UNITED STATES PATENT OFFICE.

RICHARD D. WATSON, OF ROCHESTER, MICHIGAN.

ROOFING-TILE.

946,177.

Specification of Letters Patent. Patented Jan. 11, 1910.

Application filed August 3, 1908. Serial No. 446,534.

To all whom it may concern:

Be it known that I, RICHARD D. WATSON, a citizen of the United States, residing at Rochester, county of Oakland, State of Michigan, have invented a certain new and useful Improvement in Roofing-Tiles, and declare the following to be a full, clear, and exact description of the same, such as will enable others skilled in the art to which it pertains to make and use the same, reference being had to the accompanying drawings, which form a part of this specification.

This invention relates to roofing tile.

It has for its object an improved tile to be used for covering roofs, side walls and in similar locations in the construction of buildings.

In the drawing,—Figure 1, is a longitudinal section of a number of tiles as they appear in place on the roof slats. Fig. 2, is an upper plan view. Fig. 3, is a reversed plan view. Fig. 4, is a side elevation. Fig. 5, is a cross section on the line *b*, *b*, of Fig. 2. The section shown in Fig. 1, is taken on the longitudinal sectional line *a*, *a*, of Fig. 2.

The tile 1, consists of a rectangular block of artificial stone material, preferably composition made from Portland cement and sand, and is provided on the upper side with convex flutings which broaden at the base or exposed end of the tile and narrow nearly to a point at the top or covered end of the tile. Between the flutings 2, 3, is a tabular plane 4, which is a plane surface on the upper or partly exposed side of the tile. On the under side the end 4, of the tile has its lower face inclined to the upper face with the thinner edge toward the covered end of the tile and with the thick edge or the thickened portion intermediate the two ends of the tile at the line 6, 6. Along this line the drop from the lower face of the tile is substantially equal to the thickness of the upper edge of the tile so that the body of the tile from the upper edge to the lower edge constitutes a block of substantially uniform thickness with a thickened intermediate portion narrowing from the inner line 6, 6 toward the upper end.

Opposite the convexity 2, 3, are cavities 2^a, 3^a, which rise above the general under surface of the tile. Between the cavities 2^a, 3^a,

is a rectangular cavity 7, extending deep enough in the body of the tile to form a chamber for the reception of nail-heads 8, which are driven through the nail-holes 8, in the edge of the under-lying tile. The cavity 7, extends in longitudinal length under the tile sufficiently to cover the two nail-heads of an under-lying tile and sufficiently wide to cover the four nail-heads of the two under-lying tile, and the use of this cavity avoids the necessity of driving the nails entirely home or setting the heads down close to the tile body and consequently avoids the liability of breaking or cracking the tile by driving the nail-heads home. The inclined under surface of the upper portion of the tile brings that face of the tile into close contact with the roof boards 9, upon which the tile is fastened and brings the under-lying face of the over-lying tile into close contact throughout its extent with the covered upper face of the under-lying tile next adjacent to it, and prevents the liability of breaking the tile when pressure is exerted on its upper surface by walking thereon or placing scaffolding or ladders upon or against this portion of the tile.

What I claim is:

1. A tile having its exposed face inclined to the central plane thereof, the inclination being continuous from one end to the other, and this surface having tapering convex flutings the entire length thereof, and having its under face terraced transversely intermediate the ends thereof, one of the sections thus constituted being plane and adapted to lie in intimate contact with the roof, and the other section having truncated concaved flutings adapted to engage over those portions of the convexed flutings on the exposed surface of the adjacent tile immediately therebeneath, and having between said truncated flutings a cavity for covering nail heads projecting above the adjacent surface of an underlying tile, substantially as described.

2. A generally wedge shaped tile, having its outer and under surfaces inclined with respect to one another, the otherwise plane outer surface being provided with longitudinally extending convex flutings complementary located with respect to similar though

abbreviated concave flutings in one end of the under surface thereof, and the fluted portions of the under surface having between them a cavity adapted to cover nail heads projecting above the surface of an underlying tile, and the opposite end of the under surface from that wherein said concave flutings are located being plane and adapted to

lie in intimate contact with the roof, substantially as described.

10

In testimony whereof, I sign this specification in the presence of two witnesses.

RICHARD D. WATSON.
